J. S. CANTELO.

CASTER.

APPLICATION FILED DEC. 1, 1916. RENEWED DEC. 10, 1919.

1,348,150.

Patented Aug. 3, 1920.

UNITED STATES PATENT OFFICE.

JOHN S. CANTELO, OF BOSTON, MASSACHUSETTS.

CASTER.

1,348,150.

Specification of Letters Patent.

Patented Aug. 3, 1920.

Application filed December 1, 1916, Serial No. 134,256. Renewed December 10, 1919. Serial No. 343,816.

To all whom it may concern:

Be it known that I, JOHN S. CANTELO, a citizen of the United States, and resident of Boston, county of Suffolk, State of Massachusetts, have invented an Improvement in Casters, of which the following description, in connection with the accompanying drawings, is a specification, like characters on the drawings representing like parts in each of the several views.

This invention relates to casters, and while having other and more general fields of usefulness, is well adapted for embodiment in a caster for shoe racks such as are used in transferring shoes from one department of a factory to another in the process of manufacture. As a shoe rack is thus moved about in the factory, the wheels of its casters are apt to gather up particles of thread, cloth, lint and like waste and become clogged up, occasioning much annoyance and difficulty in removing the same. This is especially apt to be the case with the waxed threads which are commonly found on the floors of the factory. A prime object of the invention is to provide an improved form of guard device coöperative with a specially formed caster wheel adapted to prevent threads or other waste debris or fibers from getting into the caster wheel or interfering with the rotation thereof. A further object is to provide an especially strong and reliable caster capable of withstanding much rough usage and of long durability. A still further object is to provide an improved mounting of the caster wheel or wheels with special provision for lubrication thereof. A still further object is to provide a caster of the type set forth with improved provision for permitting a limited, lateral swing of the caster wheel or wheels. The foregoing and other objects and features of the invention will be better understood from the following detailed description taken in connection with the accompanying drawings and will be thereafter pointed out in the appended claims.

Referring to the drawings.

Figure 1 is a front elevation showing a preferred form of my improved caster.

Fig. 2 is a side elevation thereof.

Fig. 3 is a transverse vertical section on line 3—3 of Fig. 2.

Fig. 4 is a vertical section on line 4—4 of Fig. 1.

Fig. 5 is a fragmentary detail side eleva-

tion showing a somewhat modified form; and

Fig. 6 is an edge or front view of the form shown in Fig. 5.

My improved caster is formed with a bracket frame or casting 10, consisting in a main upright portion which may be cylindrical, formed with a circular top flange 11, fitting into a circular recess 12 on the inner side of a backing plate 13, adapted to be secured to a base member "B," of the rack or other structure to be supported. Various means may be employed for securing the plate 13, to the base of the rack, but preferably and as herein shown, a stout bolt 14, is threaded through the member "B," and the plate 13, the lower portion of this bolt passing through a sleeve 15, which depends from the plate 13, being shown as integral therewith and is engaged at its lower end by the head 16, of the bolt. Other secondary bolts or screws, (not shown), may also be employed to pass through projecting portions of the plate 13, into the base member "B," to hold the plate 13, secure. The sleeve 15, fits into a socket recess in the top of the casting 10, and thus constitutes the external bearing for the swiveling of the caster. The flange 11, is retained in the socket 12, by suitable means shown as a clip 17, secured by a rivet 18, to the plate 13, and extending under the edge of the flange 11. The frame or casting 10, has at its lower portion a pivot bolt 19, fixed thereto and projecting therefrom, this bolt serving as a pivot and support for a yoke frame 20, having bearing against a flattened face 21, of the frame 10, and being held thereto by the head 22, of bolt 19. The yoke frame 20, has laterally projecting portions in which are fitted two oppositely projecting headed pivot pins 23, 24, for the two caster wheels, the heads 25, of these pins as shown facing each other in spaced apart relation in an enlarged cylindrical recess 26, which may extend in from one side of the yoke frame. As a convenient method of fitting these pins in said yoke frame, the head of one of the pivot pins 23, may be fitted to the bottom of the socket 26, somewhat beyond the transverse center of the yoke frame, while the head of the other pivot pin 24, is correspondingly spaced at the other side of such center, the pin 24, being fitted on a sleeve 27, which may have a driving fit into the socket 26 so as to hold the pin 24, from outward displacement.

The projecting portions of the pins 23, 24, have fixed thereon, like caster wheels 28, each of these wheels having outwardly projecting hubs 29, equipped with stiffening fins or ribs 30, the outer edge of which may be rounded as seen at 31, to insure the throwing off of threads that may be encountered thereby. The yoke frame 20, may have its lateral bearing extensions for the pivot pins 10 equipped with flange heads 32, presenting extended flat bearing faces to engage corresponding faces at the inner sides of the wheels 28.

In accordance with my invention, each of 15 the casters has its tread or rim face formed with one or more grooves 33, extending therearound and for coöperation with these wheels a guard plate 34, is provided having ears 35, formed with edges 36, adapted to 20 fit against the periphery of the wheels 28, and having projections 37, adapted to fit closely into the grooves 33, of said wheels. The guard plate 34 is fixed as by rivets 38, at the front of the bracket 39, upstanding 25 from the yoke frame 20. The bracket 39 also serves as a stop element for limiting the extent to which the yoke frame 20, may swivel on the pins 19, and for this purpose it is embraced at its opposite sides by flange 30 projections or ears 40, extending laterally from the casting 10 and spaced a little distance from the respective sides of the bracket 39, as seen at 41. The bracket 39, has its lower portion formed to closely fit 35 the inner contour of the caster wheels as indicated at 42, so as to prevent the carrying of any thread particles at the inner sides of the wheels. For properly lubricating the bearings of the pivot pins 23, 24, in the yoke frame, an oil passage 43, may be formed to extend into the space in the 40 recess 26 between the heads 25, this space desirably being filled with waste or other retaining material. An oil cup or well 45 formation 44, may be provided on the yoke frame around and underneath the passage 43, so as to retain and distribute the lubricant.

It will be understood that while the guard 50 plate 34, equipped with projections 37, fitted into the grooves 33, is a practicable and efficient form of the invention, other means may be employed to coöperate with the wheel grooves 33, for the purpose intended 55 *i. e.*, to insure the catching and drawing of any waxed threads or other waste that might cling to the periphery of the wheels. Thus, in Figs. 5 and 6, I show a form wherein the caster wheels 28' have for coöperation 60 with the peripheral grooves 33' thereof, a rod formed as a loop or band 45, extending around the lower half of the wheels and engaged in said grooves the upper ends of said loop or band being held by a bracket

member 46, carried by the main frame or 65 casting 10.

It will be understood that in use any waste matter such as waxed threads that might catch on the periphery or tread of the 70 caster weels, will be removed by the projecting scraper portions 35, of the guard 34, and that by the provision of the central projection 37, extending into the groove 33, it is not necessary that the scraper portion 35 should engage so closely with the 75 wheel periphery as would otherwise be the case, since any amount of thread or like waste catching on the wheel tread would quite certainly extend across the groove 33, at some portion and hence be removed by 80 the projection 37, even though it might not be engaged by the rest of the edge of the scraper 35. In like manner the encircling rod or band 45, in the form of Fig. 5, accomplishes the same purpose insuring the removal of waste threads as soon as they come 85 in contact therewith, the essential feature in each case being the provision of a relatively fixed guard member having a portion extending inward of the tread or periphery 90 of the wheel and in close proximity thereto for the purpose stated. The provision of outside fins or ribs with the curved edges 31, insures the throwing off of any waste 95 that might be caught at the outside of the wheel, while the close engagement of the bracket 39, with the inner sides of the wheels in conjunction with the flange bosses 32 prevents any waste from clogging on the inner 100 sides of the wheels. Since the yoke frame 20, with the caster wheels thereon is permitted a limited swinging on its axis pin 19, within the limits permitted by the play of the bracket web 39 between the ears or lugs 40, the caster wheels may thus adjust 105 themselves to unevenness and inequalities in the floor over which they pass. It is to be noted that the bracket web 39, is of substantial construction and that the lugs 40 engaging therewith are also of substantial 110 dimension so that liability of breakage from chucking of the parts from side to side is avoided. By the provision of the stout 115 pivot bolt 14, which is of course of malleable metal inserted through the cast backing plate 13, a strong and substantial pivot post is provided for the swiveling of the frame casting 10 of the caster so that likelihood of breakage of this pivot is obviated. It will be observed that a substantial space 120 is provided between the heads 25 of the pivot pins 23, 24, wherein a supply of lubricant adequate for a long period may be stored, so that the caster does not require any frequent attention in this respect. 125

I do not desire to be limited to the precise structural details herein exhibited and therefore desire the present embodiment to

be considered as illustrative and not restrictive, referring to the appended claims rather than to the foregoing description to indicate the scope of the invention.

5 Having described my invention, what I claim as new and desire to secure by Letters Patent is:

1. A caster comprising a body having a pair of spaced apart wheels carried thereby, 10 each of said wheels equipped with axis pins fixed thereto, having heads at the projecting ends thereof, a mounting for said wheels on said body, having bearings and a cavity to hold said axis pins with the head thereof 15 facing each other and spaced apart to afford a lubricant containing space.
2. A caster comprising a body having a yoke frame pivoted thereto with a capability of limited lateral swing, and a pair of spaced apart wheels journaled in said yoke frame, each having a pin fixed thereto, and journaled in said yoke frame, said pins having heads at their inner ends spaced apart in a cavity of said yoke frame adapted to receive lubricant.
3. A caster comprising a body having a wheel journaled thereto equipped with a guard adapted to prevent the clinging of waste to the tread thereof, said wheel having stiffening fins at its outer side with the edges thereof rounded to prevent clinging of waste or the like thereto.
4. A caster comprising a body having a wheel journaled thereto, a backing member 35 having swiveled engagement with said body, and a web projecting from said body bearing a guard member having engagement with said wheel, the sides of said web being formed and arranged to closely fit the inner 40 side of said wheel.
5. A caster comprising a body having a pair of spaced apart wheels journaled thereto, a backing member to which said body is swiveled, a web projecting from said body 45 between said wheels and bearing a guard member to coöperate with said wheels, said web having its side edges formed to closely fit the inner sides of said wheels to prevent the clinging of waste and debris thereto.
6. A caster as herein described having a wheel carrier containing a journal box parallel with its length, the carrier being combined with two wheels journaled thereto at its ends, said carrier having a web or 55 plate integral with its upper side and extending upwardly and above the periphery of the wheels, said web or plate having a scraper attached thereto at its upper end and passing transversely over and adjacent the periphery of the wheels for the purpose of removing debris or other obstructions that might adhere to the tread of said 60 wheels.
7. A caster as herein described having a wheel carrier containing a journal box parallel with its length, the carrier being combined with two wheels journaled thereto at its ends, said carrier having a web or plate integral with its upper side and in parallel line with the length thereof also 70 extending upwardly and above said wheels, said carrier being journaled to the lower end of a vertical pivot socket by means of a bolt or pin passing transversely through said carrier and through said pivot socket uniting the same in swiveled relation with each other, said vertical pivot socket being flanged at its upper end, also a lateral flange approximately midway of its length, said lateral flange being recessed sufficiently deep to receive the thickness of the upper end of said web or plate, said recess being wider than the web or plate for the purpose of limiting the right and left radial swing of the carrier on the axes of said journal bolt or pin 75 for the purpose of adjusting said wheels to floors of uneven surfaces.
8. A caster as herein described having a cap or pivot plate with a depending circular flange and circular recess within said flange, 80 and a pivot extending downward therefrom, said pivot having a hole therethrough and through said cap or pivot plate for the purpose of a reinforce bolt of malleable iron or steel, said bolt passing upward through 85 said pivot and said plate and provided with a nut on the upper end thereof for the purpose of reinforcing said pivot and uniting said plate to a base frame.
9. A caster as herein described having a 90 carrier containing a journal box parallel with its length, the carrier being combined with two wheels journaled at its ends, said carrier having a web or plate integral with its upper side and in parallel line with the 95 length thereof also extending upwardly, said carrier being journaled to the lower end of a vertical pivot sleeve by means of a bolt or pin, said pivot sleeve being provided with a flange on its upper end and is journaled to a reinforced pivot extending downward from a circular recess formed by a dependent flange, said flange being integral with a cap or pivot plate, said plate having a boss at one side thereof level with the edge 105 of the dependent flange, said boss having a screw inserted therein for the purpose of holding a washer, said washer overlapping the top flange of the vertical pivot sleeve 110 for the purpose of holding said sleeve in 115 relation with said pivot.
10. A caster as herein described, having a wheel carrier containing a journal box parallel with its length, the carrier being combined with two wheels journaled thereto at its ends, said carrier being in combination with a socket pivoted thereto, said socket being in combination with a vertical 120

pivot on which it rotates, said pivot being integral with a plate at its upper end, said plate being provided with suitable means for holding said socket in relation with said pivot as set forth.

11. A caster as described, having wheels equipped with circumferential grooves in combination with a scraper with its edge extending approximately downward adjacent 10 and transverse the periphery of said wheels, said scraper having teeth extending below the lower edge thereof for the purpose of engaging in the grooves of said wheels approximately above or over the

axes of the same for the purpose of removing debris or other obstructions.

12. A caster as described, having a body in combination with a pivot socket also two wheels journaled to each side of the body, said body being provided with a scraper 20 fixed thereto passing across and adjacent the periphery of said wheels and approximately over the axes of the same for the purpose of removing debris from the treads of the wheels.

In testimony whereof, I have signed my name to this specification.

JOHN S. CANTELO.
